DRUM MOUNTED CUTTER BIT AND
BREAKER FOR MINING MACHINES

Frank Cartlidge, Chicago, Ill., assignor to Goodman Manufacturing Company, Chicago, Ill., a corporation of Illinois

Application January 19, 1951; Serial No. 206,797

5 Claims. (Cl. 262—9)

1

This invention relates to improvements in coal mining machines particularly adapted for cutting and dislodging coal from the solid working face of a mine.

The principal object of the invention is to provide a rotary cutter head for machines of the character above described, including a novel form and arrangement of longitudinally spaced kerf cutting discs and core breaking rollers for breaking out the cores left in the working face of a mine between the adjacent kerf cutting discs.

A further object of the invention is to provide an improved arrangement for rotatably mounting the core breakers on the rotary cutter head to provide more adequate bearing support for said core breakers.

A further object of the invention is to provide an improved arrangement of core breaking rollers at different sides of said discs so as to tend to equalize the axial thrust on the cutter head resulting from engagement of the several core breaking rollers with the coal.

Other objects of the invention will appear from time to time as the following description proceeds.

The invention may best be understood by reference to the accompanying drawings, in which:

Figure 1 is a fragmentary top plan view of the front end of a cutter frame constructed in accordance with my invention;

Figure 2 is a side view of the parts shown in Figure 1;

Figure 3 is an enlarged detailed section taken on line 3—3 of Figure 1;

Figure 4 is an enlarged detailed section taken on line 4—4 of Figure 1.

Referring now to the embodiment of my invention illustrated in the drawings, Figure 1 shows the front part of a cutter head for a continuous mining machine of the kind broadly disclosed in my copending application bearing Serial Number 116,684, filed September 20, 1949, wherein a cutter frame is pivotally connected at its rear end for pivotal swinging movement relative to the main frame of the mining machine, with a rotary cutter head extending across the front end of said frame for cutting.

The cutter frame shown herein includes two side frame members 11, 11 having a cutter head, indicated at 12, mounted for rotary movement on a transverse axis between the front ends of said side frame members. The side frame members 11, 11 are cross-connected rearwardly of the rotary head 12 by a tie bar 13 pivotally connected to piston rods 14, 14 associated with hydraulic elevating cylinders 15, 15 on the machine frame (not

2

shown) for raising or lowering the cutter head during the cutting operation. Since the present invention relates only to the construction of the rotary cutter head, only the front end of the cutter frame is shown and described herein.

The rotary head 12 has a hollow drum 18 extending the length thereof, with a plurality of generally similar, radially extending, kerf cutting discs 19, 19 fixed in longitudinally spaced relation therealong. Each of said kerf cutting discs is provided with a plurality of projecting bit holders 20, 20 around its periphery, arranged to receive cutter bits 21, 21 disposed at varying angles to the plane of said disc, so that each disc cuts a separate kerf in the coal, as indicated at 25 in Figure 1, in advance of the machine when the cutter head is swung vertically.

The rotary head 12 has suitable anti-friction bearing means at opposite ends thereof, for rotatably mounting the same between the side frame members 11. As shown in Figure 1, the hollow drum 18 has enlarged end portions 28 which surround inwardly projecting sleeves 29 formed in the side frame members 11, with anti-friction roller bearings 30, interposed therebetween. A center tie rod or shaft 31 extends the length of the drum 18 and has its opposite ends fixed in the sleeves 29 and held therein as by bolts 32, passing through the outer faces of each side frame member 11, to tie said frame members together at the front end of the cutter frame.

The rotary cutter head may be driven, as usual, through a pair of cutter chains 35, 35 guided for orbital movement along the side frame members 11 and trained about sprockets 36, 36 fixed to the outer ends of the rotary head. In the form shown, the sprockets 36 are formed separately from the enlarged end portions 28 of the rotary head and are suitably fixed to the latter as by a plurality of bolts 39, 39.

Each of the sprockets 36 have teeth 40, 40 which engage in recesses 41 formed in the under faces of the cutter blocks 42 of the cutter chain. The cutter blocks 42 are pivotally connected together as usual by links 43. The cutter blocks have cutter bits 44, 44 mounted therein at several angles to the orbital plane of said cutter chain to cut a vertical kerf, as indicated at 45 in Figure 1, at each end of the cutter head. The sprockets 36 and cutter blocks 42 are of such dimensions as to cut the outermost kerfs 45 at approximately the same depth as the intermediate kerfs 25 formed by the cutter discs 19, but said outermost kerfs may be formed somewhat wider than the intermediate kerfs, as shown.

The cutter chains 35 may be driven by power through suitable drive sprockets on the machine, mounted as usual concentrically with the axis of vertical swinging movement of the cutter frame 10. The cutter chain driving mechanism may be of any conventional form so need not be further shown nor described in detail.

The side frame members 11, 11 may include extension plates 47, 47 at their front ends, which are longitudinally slideable relative to side bars 48, 48, to provide the usual cutter chain tensioning adjustment.

One or more core breaking members 50, 50 are associated with each of the cutter discs 19, so that their outer ends project into the kerf formed by its respective cutter disc.

Each core breaker comprises a roller 51 with a supporting stub shaft 52 projecting concentrically from the base thereof. The rollers are preferably frusta-conical in form, although they may be of other forms as long as they are freely rotatable in the kerf. Each stub shaft 52 is journaled on an elongated bearing 53 formed transversely along the surface of the drum 18 so that the axis of rotation of each roller and its stub shaft intersects the surface of the drum along a secant which is offset radially a substantial distance from the longitudinal axis of the drum. Thus, the shafts 52 of the two rollers are spaced from the axis of the drum 18 so as to clear opposite sides of the centering shaft 31 of the drum. Each elongated bearing 53 is also offset laterally from one side of its respective cutter discs, but with the axis of rotation of the roller and shaft disposed at an acute angle to the plane of rotation of said cutter discs so that the roller itself extends toward and partially into a recess 54 formed in the periphery of the cutter disc, as shown in Figures 1 and 4.

The arrangement just described is such that the base of each roller 51 projects laterally of one side of the disc beyond the line of clearance defined by the cutter bits 21 in cutting the kerf at said one side of said disc, but with the tapered outer end and the major portion of the roller disposed within the lines of clearance at both sides of said cutter disc. As a result of this arrangement, the outer end of each roller will project into the kerf 25 cut by the cutter disc, and the laterally projecting base of the roller is free for rotation as it engages and breaks off projecting portions of the core which may be left between adjacent kerfs.

The elongated bearings 53 for the roller shafts 52 each consists of a generally semi-circular, hollow boss formed integrally with the drum 18. A bearing sleeve 56 is mounted in one end of said boss, having a flange 57 for receiving longitudinal thrust on the tapered roller 51. A second, smaller bearing sleeve 58 is mounted in the opposite end of said boss, for receiving a reduced end portion of the shaft 52 (see Figure 3). Each shaft 52 may be held in its bearings by any suitable means, such as a retaining ring 59, engaging the outer end face of the bearing sleeve 58 and secured by a U-shaped locking ring 60 of well-known form, detachably fitting in an annular groove 61 at the outer end of said shaft.

In the preferred arrangement shown herein, each cutter disc 19 has two core breaker rollers 50 associated therewith, said rollers being mounted on opposite sides of the hollow drum 18 so that the axes of said rollers and their associated stub shafts are disposed in substantially

parallel planes offset radially on opposite sides of the longitudinal axis of the drum, as shown in Figure 4.

The several rollers 50 are preferably arranged 5 on the cutter head so that some of them project toward similar sides of the cutter discs, and a substantially equal number of the rollers project toward opposite sides of the discs. For instance, in the embodiment shown in Figure 1, where five 10 cutter discs 19 are employed, the four rollers on the two cutter discs at the left-hand side project toward the left end of the cutter head, as viewed toward the front of said cutter head, while the 15 corresponding four rollers on the two cutter discs on the right-hand side project toward the opposite or right end of the cutter head. The center cutter disc has one roller projecting toward the left end and the other roller projecting toward the opposite or right end of the cutter head. With this arrangement, the end thrust 20 on the cutter head produced by lateral rolling engagement of the several rollers with the intermediate cores between the kerfs 25 will be substantially equalized, so as to overcome any tendency of the cutter head to slew in one direction 25 or the other during the cutting operation.

The use and operation of the cutter head with the core breaker rollers mounted thereon, as above described, will now be apparent to those 30 skilled in the art.

The arrangement wherein the rollers with their 35 stub shafts 52 disposed on off-center relation to the axis of the drum 18 makes it possible to provide much longer and more substantial journal bearings for the rollers than in previous 40 structures wherein the roller shafts have usually been disposed with their axes extending in a generally radial relation to the longitudinal axis of the drum. As a result of this arrangement, the core breaking rollers can present larger, more 45 effective core breaking areas to the coal than heretofore.

It will be observed further that the outer or 50 free end of the rollers are biased toward the plane of rotation of their adjacent cutting discs, so that the laterally projecting base portions of the rollers engage the cores between the discs at an oblique angle, thus producing a distinct wedging 55 action on the cores, effective longitudinally of each roller toward its base, in addition to the usual tangential rolling action effective upon the rollers. This longitudinal wedging action is especially effective when the rollers are of conical form, as shown. Accordingly, in performing 60 their function, the rollers are subjected to a substantial amount of end thrust, thereby relieving the rollers of a substantial amount of circumferential shearing stresses which, otherwise, they and their bearing supports would be required to 65 withstand if their axes were disposed generally diametrically of the drum, as in previous structures.

By providing a substantially equal number of 70 core breakers on opposite sides of the several intermediate kerf cutting discs, any tendency of the cutter head to slew sidewise during the cutting operation is effectively eliminated. Moreover, the arrangement, whereby all the rollers nearer each end of the rotary cutter head are disposed on the outer sides of their respective cutter discs, tends to spread the coal broken away from the cores between adjacent intermediate kerfs 25 toward the larger end kerfs 45 produced 75 by the cutter bits 44, 44.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a cutter head for a mining machine, a rotary drum having a plurality of radially extending cutter discs spaced laterally therealong to cut a plurality of spaced kerfs, and rollers rotatably journaled on said drum with their axes offset and spaced radially from the axis of rotation of said drum, and disposed at an acute angle to a plane perpendicular to said drum axis, the outer ends of said rollers farthest from the drum axis terminating within the lateral kerf cutting limits of their respective cutter discs, and with the base portions of said rollers projecting beyond the lateral kerf cutting limits of their respective cutter discs.

2. A cutter head structure in accordance with claim 1, wherein said rollers are tapered and journaled on the drum laterally of their respective discs, with the smaller outer ends of said rollers extending toward the peripheries of their respective cutter discs, and disposed substantially within the kerf-cutting limits of the latter.

3. A cutter head structure in accordance with claim 1, wherein said rollers have stub shafts journaled on said drum with their axes extending along secants intersecting the periphery of said drum, and each of said shafts have bearing supports spaced on opposite sides of a line perpendicular to its respective secant and intersecting the axis of rotation of said drum.

4. In a cutter head for a mining machine, a tilting frame including a pair of laterally spaced side bars, a drum rotatably mounted on said frame between said side bars having a plurality of spaced kerf cutting discs, a tie rod extending through said drum substantially concentrically therewith for connecting said side bars, and core breaking rollers having stub shafts journaled in bearing supports on said drum extending

transversely of the latter, with said stub shafts spaced radially from and extending transversely of said tie rod, at an acute angle to a plane perpendicular to said drum axis, the outer ends of said rollers farthest from said tie rod terminating within the lateral kerf cutting limits of said cutter discs, and the base portions of said rollers projecting beyond the lateral kerf cutting limits of their respective cutter discs.

- 10 5. In a cutter head for a mining machine, a rotary drum having a plurality of radially extending cutter discs spaced laterally therealong, each of said discs having a plurality of cutter bits fixed on its periphery and extending at different angles therefrom to cut a kerf substantially wider than the body of said disc, said cutter disc bodies also having breaker roller apertures therein, and conical breaker rollers each having a stub shaft journaled on said drum with their axes offset from the axis of said drum and disposed at an acute angle to an adjacent cutter disc, the major portion of said conical roller projecting into a roller receiving aperture in said disc, with the enlarged base portion of said roller projecting substantially beyond one side of the kerf cutting limits of the cutter bits of its cutter disc, and with the remainder of said conical roller including its tapered outer end disposed within the kerf cutting limits of said bits, so that rolling engagement of said roller against the adjacent wall of the kerf cut by its disc will normally be confined to one side of said conical roller adjacent its base.
- 15 20 25 30 35

FRANK CARTLIDGE.
